UNITED STATES PATENT OFFICE.

PIERRE ANSELME IGNACE CUVELIER, OF HAUBOURDIN, FRANCE.

AGGLOMERATING MACHINE.

Application filed February 29, 1924. Serial No. 696,027.

To all whom it may concern:

Be it known that I, PIERRE ANSELME IGNACE CUVELIER, citizen of the Republic of France, residing at 79 Place de l'Hospice, 5 Haubourdin, Nord, France, have invented new and useful Improvements in Agglomerating Machines, for which I have filed applications in France, Mar. 27, 1923, now issued as French Patent 564,397, and in Great 10 Britain, Dec. 21, 1923, Serial No. 32,112, 1923, and of which the following is a specification.

The present invention relates to a machine for moulding building blocks of the type 15 utilizing a ramming mechanism combined with a jiggling or vibratory mechanism. It is specially designed for the manufacture of hollow building blocks, though its field of operation may be extended to any kind of 20 blocks, whatever may be their form and dimensions.

The accompanying drawing shows by way of example a form of execution of the machine according to the invention:

25 Fig. 1 is a front elevation of the machine, partly in section, showing: The controlling means for the ramming mechanism and for the mechanism for removing the cores from the mould, this latter operation being effected by the press-cylinder which also serves for the two jiggling or vibratory operations,

And also showing device for removing the cores from the mould and the like.

35 Fig. 2 is a sectional plan of the lower portion of the machine.

Figs. 3 and 3^a, read together, show a side elevation of the machine.

40 Fig. 4 is a plan view of the upper portion of the machine and,

Fig. 5 is a perspective view of a block manufactured by the machine.

The agglomerating machine, shown in the drawing, comprises four guides 1 which are 45 fixed to the core-removing frame 2 surrounding the mold. The mould consists of two lateral walls 3 (Fig. 1) of an end wall 4 and front wall 5 (Fig. 3^a). The bottom 6 of the mould comprises a removable plank 6 which 50 rests upon a stay 7 supported by a cross piece fixed to the frame of the machine and engages at 8 in a notch formed in the base of the lateral walls 3 of the mould. The frame of the machine is formed by guide columns 9, serving as guides for the frame 11 of the rammer 10. The columns 9 also

support a cross bar 12 which carries the fixed casing 13 of the press-cylinder, the controlling mechanism 14, 15 for the compressed fluid, the ram-cylinder 16, and the 60 press-cylinder 17. The press cylinder 17 is carried by a movable cross bar 17' which in turn is connected by bars 18 and stays 19 to the core-removing frame 2. The press-cylinder 17, through the connections 18 and 19, serves to impart a jiggling or vibratory motion to the frame 2 and also to remove the cores from the mould.

The core-removing frame 2 surrounds the mould during the ramming and jiggling operations and catches 20 engaging projections 21 on the mold connect said frame and mold together during these operations. The mould carries projections 21 and 22, by which the mold may be engaged to transport 75 it from the machine to the drying apparatus.

With this end in view, the projections 22 of the mould rest upon the elevating frame 23 of a transporter carriage, the fixed frame 24 of which has supporting grooved wheels 80 moving upon triangular rails 25 fixed to the frame of the machine at its extremity.

The mold, comprising the parts 4, 5, 6, is divided interiorly into a series of compartments, each of which constitutes a mould- 85 element for moulding one or more blocks.

In the present case, (Figs. 1 and 2) these mould-elements are four in number, each of which can mould two blocks. One of these blocks is shown in horizontal section at the 90 upper left-hand corner of Fig. 2 and in perspective in Fig. 5. 28 represents the internal divisions of the mould; 27 shows the cores forming the hollows in the blocks; 26 represents the bars rigidly fixed to the cores 95 by angle-irons and connecting these cores together; these bars, as well as the divisions 28, passing freely through vertical slots 47 (Fig. 2) formed in the top of the walls of the mould, the ends of said bars and divisions being fixed to the frame 2, the entire assemblage of these bars, divisions and cores forming a rigid partitioned structure which, with a view to removing the cores, as will be described below, and to transporting the mould, from which the cores have been removed, to the drying room, can be moved vertically relative to the mould.

100 30 (Fig. 3) designates the feed-hopper arranged in proximity to the press. The material delivered by the hopper is transferred 110 to the interior of the mould by means of a

transporting carriage giving measured quantities, the frame of which is shown at 39 (Figs. 1 and 3^a). This carriage runs upon a horizontal track, parts of which rest upon the frame 2 (Fig. 1) while the remaining aligning sections are fixed to the frame supporting the hopper. The transporting carriage 39 is actuated by a compressed-air cylinder 29 (Figs. 3, 3^a) having a piston 29^a connected by a piston rod 29^b to said carriage 39. The carriage 39 is fitted with prismatic compartments 44 constituted by sheet metal plates or shutters 42 which can pivot about axes 41 in the adjustable bearings 40 of the carriage. These cavities, whose number and arrangement correspond to the rows of blocks to be moulded, receive in succession the mixture from the hopper during the movement of the carriage below said hopper, as will be seen below, and then discharge it into the mould, when the carriage has been brought into position above them, by the simultaneous manipulation of the shutters 42. For this purpose the shutters are subjected at their lower ends to the motion of helicoidal cams 35 carried by a shaft 34 journalled in the carriage 39 and provided with a hand-wheel 33, these cams being so arranged as to open or close the shutters 42 at will, according to the direction of rotation of the hand-wheel. Each pair of cams 35 comprises two helical parts extending only upon a portion of the periphery of the shaft 34 and of opposite pitch and the shutters tend to open under the excess of the weight of their lower parts when empty, as well as when full, so that extensions 42^a formed on their lower ends bear constantly against said cams, the pitch of these latter, combined with the friction on the shaft 34, being such that said shaft always remains in any position into which it has been brought. When the shutters 42 are opened by means of the hand-wheel 33 the material contained in the cavities 44 falls into the moulds, being preferably guided in its fall by the inclines 45 with which the cores 27 are provided (Figs. 1 and 3^a).
 In order to vary the extent to which the cavities 44 can be filled, additional metal plates 43 are preferably mounted, so as to be able to slide, upon the plates or shutters 42.
 The carriage is filled automatically during its passage under the hopper 30, the register 31 of which opens and closes by means of abutments. The carriage 39 also actuates, by any suitable means, the discharge and distributing vanes 32 of the hopper. This device has only been shown in Fig. 3^a in a diagrammatic manner and by way of example.

Filling of the moulds is effected in a plurality of stages and preferably in two stages

at equal volumes, each filling operation being followed by a jiggling or vibrating operation and then by ramming.

The vibrating or jiggling operation is effected by imparting to the frame 2, after having engaged catches 20 of said frame under the teeth 21 of the mould, a vertical reciprocatory movement by means of the press-cylinder 17 acting through the intermediary of the bars 18 mentioned above. With this end in view, air is admitted by means of the valve 14 into the press-cylinder 17 so as to raise it and consequently to raise the frame 2 and the mould, whereupon this air is allowed to escape so as to allow the press-cylinder 17 and the mould to sink. This double operation is repeated as often as necessary. In this way a series of vibrations is obtained which enables the material to pack together in the mould.

The ramming operation is effected by means of the ram 10 driven by the piston 16 mentioned above. With this end in view, the distributor 15 is actuated so as to cause the air below the piston 16 to pass to the upper face of this piston. Equilibrium is distributed by the weight of the ram 11—10 which falls into the material contained in the mould. In order to avoid the formation of ridges, which might result from the fact that certain portions of the surface of the mould have not been rammed, the head of the ram 10 has slots 10^a which engage exactly with the connecting bars 26 and the divisions 28 and the height of these bars 26—28 is such that after the second or final filling of the moulds, the upper level of the said bars is flush with the surface of the non-rammed concrete, whereas after the second ramming and before final removal from the mould, their lower level is flush with the level of the compressed block. It follows that the portions under the bars and divisions 26, 28 which are consequently not rammed, are finally at the same level as the rammed portions, whereby the formation of portions in relief is avoided.

After this second ramming operation the cores as well as the internal partitions are removed from the mould by means of the same apparatus as was used for the jiggling operation, that is to say, by the help of the press-cylinder 17 and the devices 18, 19, 2, 26, but after having disengaged the catches 20 from the lugs 21 so that the mould remains in place. In this movement, the assemblage of the cores 27, their attaching bars 26 and the internal divisions 28 of the mould slides through the head of the ram until it contacts with the frame 11. At this moment, the base of the cores stands some distance above the level of the mould and this latter can therefore be easily removed and transported to the drying room.

The transportation of the mould to the

drying room is effected by means of a carriage 24 running on triangular rails 25 (Fig. 1) fixed to the frame of the machine. This carriage is preferably provided with an elevating frame 23 upon which the mould rests.

The operation of the machine will be understood from the above description but it may be briefly summed up as follows:

The feed-carriage is brought under the 10 hopper to be filled and is then brought directly above the mould and its contents are discharged into the mould by opening the shutters 42 by means of the hand-wheel 33.

The carriage is then brought under the hopper for the second filling and the first jigg- 15 ging operation is carried out, to be followed by the first ramming operation as described.

After the ram has been raised, the carriage is brought back in a filled condition to 20 its position above the mould and the second series of operations, namely, the filling of the mould, jiggging and ramming is effected as before, the ramming being stopped when the block has been lowered to the desired 25 height. The ram is then secured in any suitable manner. The ram being secured against movement and the base of the head of the ram 10 being in contact with the compressed blocks, removal of the cores is effected by 30 transmitting air, by means of the valve 14, into the movable cylinder 17, which rises and takes with it the cores 27 and the internal partitions 28. After the cores have been removed, air is admitted under the piston 16, 35 which results in raising the ram. There is now no obstacle to the transport of the mould 3, 4, 5, to the drying room by means of the carriage 24. When it arrives at the drying room, the mould is lowered by means of the 40 lift-carriage 23 so as to deposit the plank 6 upon a support placed thereunder. The mould is then opened, which is effected by removing the front movable wall 5 and swinging the two lateral walls 3 about the rear wall 4. After having raised the said 45 walls by means of the carriage, the mould is raised and a second plank 6 is inserted in the recesses 8 of the lateral walls of the mould and this latter is carried back again to the 50 machine, in which the accurate guiding of the fixed frame 24 upon the rails 25 ensures its correct position upon the stay 7; the device comprising the members 2, 26, 27, 28, is then allowed to descend again for the next 55 moulding operation, the frame 2 falling into the mould and the elements 26, 27, 28 falling around the mould and within the slots formed in said mould.

This machine presents, among others, the 60 following advantages:

The actuation by compressed air is applicable to the three operations of ramming, jiggging and removing the cores, these operations being combined in the same machine 65 and effected by means of controlling devices

(16, 17) which are of reduced size and are well protected from dust.

The combined jiggging and core-removing devices render it possible, while greatly reducing labour charges, to reduce to a considerable extent the number of unbaked blocks (fragile products) which are broken during their transportation from the machine to the drying room, while at the same time ensuring that the mould is positioned exactly and firmly upon the frame of the machine, which is absolutely necessary for the ramming operations.

The method of operation of the devices for removing the cores 27 and the internal divisions 28 of the mould is mechanical; on the other hand, the opening of the mould in the drying room, which is effected by hand by moving the walls apart or by removing them, enables a considerable reduction in the resistance to removing the blocks from the mould to be effected, so that it is possible to mould a greater number of blocks at a single operation. This system of removing the blocks from the mould, moreover, renders it possible to produce shaped blocks.

The blocks are generally formed to the number of eight at each operation and are practically twice as long as they are broad, and the thickness of their middle wall is generally double that of their side walls.

The invention has only been described and shown by way of example and in no way limitatively, and it is obvious that various modifications could be made therein without departing from the spirit of the invention.

I claim:

1. An agglomerating machine comprising in combination a mould, means for delivering a charge of material to said mould, means for imparting a jiggging motion to said mould and means for ramming said material in said mould, all said means being actuated by compressed air.

2. An agglomerating machine comprising in combination a mould, means for delivering a charge of material to said mould, means for imparting a jiggging motion to said mould and means for ramming said material in said mould, all said means being actuated by compressed air and the operations being effected each in two stages.

3. An agglomerating machine comprising in combination a mould, a carriage for supplying a charge of material to said mould, means for imparting a jiggging motion to said mould, and means for ramming said material in said mould, said carriage and the jiggging and ramming means being all actuated by compressed air.

4. An agglomerating machine comprising in combination a hopper for the material a mould, a carriage movable by compressed air under said hopper to receive a charge

- of material and capable of being returned by compressed air to deliver the charge to said mould, and means actuated by compressed air for imparting a jiggling motion 5 to said mould and for ramming the material in said mould.
6. An agglomerating machine comprising in combination a mould, a hopper containing the material, a carriage movable by compressed air under said hopper to receive a charge of material and adapted to be returned by compressed air to deliver the charge to said mould, means actuated by compressed air for imparting a jiggling motion 10 to said mould and for ramming the material in said mould, and means for transferring said mould to a device for transporting it to a drying mechanism.
7. An agglomerating machine comprising in combination a mould, a hopper containing the material, a carriage movable by compressed air beneath said hopper and adapted to open said hopper to receive a charge, means actuated by compressed air for returning said carriage to a position above said mould to deliver the charge to 15 said mould, means actuated by compressed air for returning said carriage to a position above said mould to deliver the charge to said mould, means actuated by compressed air for imparting a jiggling motion to said mould and for ramming the material in the latter.
8. An agglomerating machine comprising in combination a mould, a hopper containing the material, a carriage movable by compressed air into position beneath said hopper to receive a charge, means operated by said carriage to open said hopper and to 20 actuate vanes for discharging the material therefrom into said carriage, and means for returning said carriage by compressed air into position for discharging the material into the mould.
9. An agglomerating machine comprising in combination a mould, a hopper containing the material to be agglomerated, a carriage movable by compressed air into position beneath said hopper to receive a charge, means 25 operated by said carriage to open said hopper and to actuate vanes for discharging material therefrom into said carriage, means for returning said carriage by compressed air into position for discharging the material into the mould, and means operated by hand for allowing the material to fall from said carriage into said mould.
10. An agglomerating machine for making hollow building blocks, comprising in combination a mould, cores in said mould, means for delivering a charge to said mould, means for imparting a jiggling motion to said mould and means for ramming the material into said mould and a core-removing mechanism operated by said jiggling means. 70
11. An agglomerating machine comprising in combination a mould, a hopper containing the material, a carriage adapted to be moved by compressed air to said hopper to receive a charge and also by compressed air to a position above said mould, said carriage comprising pivoted plates, manually operated means for allowing said plates to swing so as to allow the charge to fall by gravity into said mould, means for imparting a jiggling motion to said mould and means for ramming said material into said mould. 75
12. In a machine of the class described the combination of a mould, a hopper containing the material to be agglomerated, a carriage adapted to be moved by compressed air under said hopper to receive a charge, said carriage comprising pivoted plates adapted to be locked in position to hold the charge. 80
13. In a machine of the class described the combination of a mould, a hopper containing the material to be agglomerated, a carriage adapted to be moved by compressed air under said hopper to receive a charge, said carriage comprising pivoted plates adapted to be locked in position to hold the charge and means for releasing said plates to allow them to pivot under the weight of said charge to allow it to fall into the mould. 85
14. In a machine of the class described the combination of a mould, a hopper containing the material to be agglomerated, a carriage adapted to be moved by compressed air under said hopper to receive a charge and to be moved by compressed air into the position above said mould to deliver the charge, the receptacles of said carriage being formed by pivoted plates, a shaft mounted in said carriage, helical surfaces on said shaft adapted to hold said plates in closed relation and manually operated means for rotating said shaft to release said plates to allow them to pivot under the weight of said charge to deliver it to the mould. 90
15. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 95
16. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 100
17. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 105
18. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 110
19. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 115
20. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 120
21. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 125
22. In a machine of the class described, the combination of a mould, a hopper containing the material to be agglomerated, a carriage adapted to be moved by compressed air under said hopper to receive a charge and to be moved by compressed air into position above said mould to deliver the charge to the mould. 130

charge, plates pivoted on said carriage to form receptacles for the charge, a shaft mounted in said carriage, helical surfaces on said shaft, a handwheel on said shaft for the purpose of rotating it to cause said helical surfaces to hold said plates in closed relation or to permit them to pivot under the weight of the charge to deliver this latter to the mould.

10 16. In a device of the class described, the combination of a mould, means for delivering a charge of material to said mould, means for ramming said material into said mould, a press-cylinder, projections on said mould adapted to be engaged by means actuated by said press-cylinder to impart a jiggling action to said mould.

15 17. In a device of the class described, the combination of a mould, means for delivering a charge of material to said mould, means for ramming said material into said mould, cores in said mould, a bar to which said cores are attached, means for imparting a jiggling motion to said mould, said jiggling means acting subsequently to remove the cores from the mould.

20 18. In a device of the class described, a mould consisting of side walls hinged together and a removable plank inserted in notches in said side walls to form the bottom of the mould.

25 19. An agglomerating machine comprising guide-columns, a ram cylinder and a press-cylinder carried by said columns, a mould, a hopper containing the material, a carriage, actuated by compressed air, to take a charge from said hopper and to deliver it

to said mould, means actuated by compressed air in said press-cylinder for imparting a jiggling motion to said mould and 40 a ram actuated by compressed air in said ram-cylinder for ramming the material into said mould.

20 20. An agglomerating machine comprising guide-columns, a ram cylinder carried by said columns, a press cylinder mounted concentrically around said ram cylinder, a mould, a hopper containing the material, a carriage actuated by compressed air to take a charge from said hopper and to deliver it 45 to said mould, means connecting said press-cylinder to said mould for imparting a jiggling motion thereto by compressed air, and a ram actuated by compressed air in said ram-cylinder for ramming the material 50 into said mould.

21 21. An agglomerating machine comprising guide-columns, a ram cylinder carried by said columns, a press cylinder mounted concentrically around said ram cylinder, a 60 mould, cores adapted to fit in said mould, a bar surrounding said mould and fixed to said cores, a hopper containing the material, a carriage actuated by compressed air to take a charge from said hopper and to deliver it to said mould, means actuated by compressed air in said press-cylinder and adapted to be connected to said mould to 65 impart a jiggling motion thereto, means for ramming the material into said mould and means adapted to be actuated by said press-cylinder and connected to said bar for removing the cores from the mould.

PIERRE ANSELME IGNACE CUVELIER.
